Andrew O'Neill, of Portsmouth, Ohio.

Assignor to

O.Neill & Hunter, of Portsmouth, aforesaid.
Letters Patent No. 740. - dated Oct. 30, 1855.

The schedule referred to in these Letters Patent, & making part of the same

To all whom it may concern,

Be it known that I, Andrew O'Neill of Portsmouth, Scioto County, Ohio, have invented or produced a new, ornamental design for Stoves, & I do hereby declare the following to be a full, clear & exact description thereof, reference being had to the annexed drawings, making part of this specification, and in which

Fig 1. represents the side plate, & one of the oven doors, the other door being counterpart.

Fig 3. represents the front with its upper fire door, & one of its lower ones, the other being counterpart.

Fig 6. represents the top-plate.

Fig 7. is a vertical section, thro' the line 7.

Fig 8. represents the hearth plate.

The margins of the doors & of the front & side plates, are decorated with notched beads. (a). Diamond shaped bosses (b) rise, one from the middle of each door. The boss in the upper fire door is surrounded by semi-spheres (c) In the other doors, each of the four spaces between the boss & the outer bead, is studded with nine semi-spheres, arranged diamond fashion,

I claim the design for doors, top, & side plates of a stove, substantially as represented,

In testimony whereof, I hereunto set my hand before two subscribing witnesses.
